UNITED STATES PATENT OFFICE.

JOHN VANDEMOER, OF EL PASO, TEXAS.

SAMPLER.

Application filed August 25, 1920. Serial No. 406,036.

To all whom it may concern:

Be it known that I, JOHN VANDEMOER, a citizen of the United States, residing at El Paso, in the county of El Paso and State of Texas, have invented certain new and useful Improvements in Samplers, of which the following is a specification.

This invention relates to samplers which are capable of deflecting or cutting out from a thoroughly and uniformly mixed body of fluids, ore, grain or other granular or disintegrated material a determined percentage of the material passing through the apparatus.

15 The objects of the invention are:—

First, to construct a sampler of the character described which will thoroughly mix the material passing through the same and at the same time cut out a sample which has 20 been so mixed in a quiet and most efficient manner.

Second, to provide a combined mixer and sampler which can be easily installed, requires small space and head room, a minimum 25 power to operate and at the same time readily permit the percentage of the material to be cut out as a sample to be varied in the shortest interval of time without in any way disturbing the operative relations 30 of its parts.

Third, to provide a sampler adapted for practical use in connection with all classes 35 of material that can flow or move over a surface whether liquid, coal, coke, sand, rock, grain, ashes or the like.

Fourth, other objects and advantages of the invention will appear from the detailed construction, assembling, and mode of operation which will be hereinafter more fully 40 described.

The invention consists of structural characteristics and relative arrangements of elements which will be hereinafter more fully disclosed and particularly pointed out in 45 the appended claims.

In the two sheets of drawings in which similar reference characters indicate the same parts in the several figures,

50 Figure 1, is a longitudinal section of the improved sampler.

Figure 2, is a section on line 2—2 of Fig. 1 when cutting a one-fourth sample.

Figure 3, is a section on line 2—2 of Fig. 1 when cutting a one-eighteenth sample.

55 Figure 4, is a section on line 4—4 of Fig. 1.

Figure 5, is an enlarged and fragmentary view of the cutting opening of the sampler.

Figure 6, is a sectional view on line 6—6 of Fig. 5. 60

Figure 7, is a longitudinal section of a modified form or duplicate sampler.

Figure 8, is a section on line 8—8 of Figure 7, and

Figure 9 is a section on line 9—9 of Figure 7. 65

Referring to Figures 1 to 6 of the drawings, S is a revolving imperforate cylinder supported by the spiders H carried by the rotating shaft I rotatably supported in 70 bearings P, resting on supports O, said shaft and cylinder are slightly inclined and are rotated by any suitable pulley Q, as shown and will be readily understood.

E is a chute which receives the material 75 to be sampled and as shown feeds said material into the upper and elevated end F of the cylinder S. G, G are ribs or other suitable obstructions or lifting devices secured on the inner side of the cylinder which are 80 adapted to repeatedly pick up the material passing through the sampler and thoroughly and uniformly mix the same before certain determined proportions are cut out forming the samples to be presently described. 85

K is an opening near the lower end M of the revolving cylinder and is provided with an adjustable gate R which can be moved or slid between suitable guiding flanges R', R', see Figs. 1, 5 and 6, by means of handle 90 X, in such a manner as to regulate the size of the opening K. One of the guiding flanges is preferably provided with a scale Z to indicate degrees, as shown in Figure 5. Said gate R may be locked or held in 95 its adjusted position by means of clamp screws Y as will be readily understood. J is a circular imperforate plate centrally arranged and attached to a spider H, of the revolving cylinder S near the opening K 100 for the purpose of preventing the material being thrown into the sample opening or hole K and impair the proper and accurate working of the sampler.

L is a chute for receiving the material as 105 it is cut out by the sampler when the opening K, of the cylinder S passes over it, while N is a second chute arranged at the lower end of the cylinder S, to receive the major and remaining material passing from the sampler, as clearly shown in Figs. 1 and 7. 110

T indicates a stationary outer casing or housing enclosing the sampler, which may be provided with any suitable closing means provided with a lock so as to prevent accessibility to the sampler or tampering with its set or adjusted positions of the cut out gates or openings.

The modification of the invention shown in Figures 7, 8 and 9 is substantially the same in its essential parts as that shown in Figures 1 to 6 inclusive, except in having one opening or sample cut out K, as shown in said Figures 1 to 6, there are two holes, openings or cut outs K and K' K", each of which openings has its own receiving chute L and L' respectively, and which modification necessarily is provided with a longer cylinder S and of larger diameter if so desired.

20 The parts being constructed and arranged, as shown in Figures 1 to 6, and the cylinder S being rotated in the direction indicated by the arrow by power being applied to the pulley Q, the material which drops through the chute into the upper end of the cylinder is taken up or elevated by the ribs G or other similar means and permitted to drop down, which action upon the material is repeated and continuous. This repeated tumbling of the material in its downward path or sliding through the cylinder is such that when the material has reached the zone in the interior of the cylinder S where the opening or cut out hole K is located, the material is thoroughly and uniformly mixed or intermingled and a certain proportion or percentage of the material passing through the cylinder S or sampler will quietly, automatically and intermittently pass through said opening or cut-out hole K into the chute L to be collected in a sample hopper, not shown. The remainder of the material will continue in its downward and sliding movement to the lower end M of the cylinder and pass by way of the chute N to any suitable storage hopper or chamber, not shown. The baffle or circular plate J prevents any material lifted by the ribs G from being thrown into the cut-out or sampling opening K before the same reaches the sampling zone of the cylinder S.

If it is desired to vary the ratio or percentage of the sample of the total material passing through the apparatus all that is necessary is to vary the cross-sectional area of the opening K which can be easily and quickly effected by sliding the gate R in its guiding flanges R' R", thereby varying in degrees along the circumference of the cylinder, the width W of the opening K, and as shown in Figure 5, the width is twenty degrees and the cut or sample will be twenty three-hundred and sixtieths or 65 one-eighteenth, if one cutting or sample hole

K is provided, and one-ninth if two holes are employed. After the gate R is properly adjusted, the clamp screws V, V, are screwed down to bind said gate to the cylinder. The dimension V or longitudinal length of the hole K is varied, depending on the size of the material passing through the sampler, and as will be readily seen any ratio, part or sample of the material, independent of the material operated upon can be secured and if materials are to be operated upon which do not readily and uniformly commingle or mix, the cylinder S is made longer and the number of ribs G are multiplied, or if desired the inclination of the cylinder S may be varied to retard or accelerate the movement of the material through the apparatus; and it has also been found in the practical operation of the invention that the distance W of the opening K should never be smaller than the distance U.

It will be apparent that as soon as the cut-out hole traverses the stream of the material passing through the sampler it will drop into the chute L and that said stream is cut normal to the direction of the stream which assures a proper operation for securing a correct sample.

In Figure 2, the cut-out opening is forty-five degrees and the cut will be one-eighth and when the opening is ten degrees, as shown in Figure 3, the cut will be one-thirty sixth part of the material handled when one opening is used, and while I have shown and described one or two openings this number could be varied without in any way departing from the spirit of the invention and will depend on the size and nature of the material being sampled.

From the foregoing disclosure of the construction and operation of the device all the objects and advantages briefly outlined in the statement of invention are fully and efficiently carried out, and while the preferred form of my apparatus has been disclosed, it is clear that many modifications will readily suggest themselves without departing from the essential elements of the invention and clearly be within the scope of the claims.

What I claim is:

1. A sampler comprising a hollow rotary inclined cylinder, means for feeding material within the cylinder at its upper end, means within the cylinder and at its upper section for mixing the material fed within the cylinder, a plurality of cut-out openings in the lower section of and rotating with said cylinder to divert to the outside of said cylinder a certain proportion of the mixed material passing through said cylinder, and means within the cylinder preventing the material while being mixed from being thrown into said cut-out openings.

2. A sampler comprising a hollow rotary

inclined cylinder, means for feeding material within the cylinder at its upper end, ribs within the cylinder and at its upper section for mixing the material fed within the cylinder, a cut-out opening in and rotating with said cylinder at the lower section and removed from that in which the material is fed and mixed to divert to the outside of said cylinder a certain proportion

of the mixed material passing through said cylinder, an adjustable gate to vary the size of said cut-out opening, and a baffle within said cylinder to prevent the material while being mixed being thrown into said cut-out opening.

In testimony whereof I affix my signature.

JOHN VANDENOER.
